UNITED STATES PATENT OFFICE.

RUSSELL T. ELWELL, OF TRENTON, NEW JERSEY.

SOLE FOR BOOTS AND SHOES AND OTHER USES.

1,101,487.

Specification of Letters Patent.

Patented June 23, 1914.

Continuation of application Serial No. 810,354, filed January 5, 1914. This application filed May 23, 1914. Serial No. 840,597.

To all whom it may concern:

Be it known that I, RUSSELL T. ELWELL, a citizen of the United States, and a resident of Trenton, in the county of Mercer and State of New Jersey, have invented an Improvement in Soles for Boots and Shoes and other Uses, of which the following description, in connection with the accompanying drawings, is a specification, like characters on the drawings representing like parts.

This application is a continuation of my co-pending application Serial No. 810,354, filed January 5, 1914.

15 This invention relates to soles for boots and shoes and other uses, and among other objects aims to provide a light, durable material. I herein use the term "sole" generically as including or meaning the entire sole including the heel or any part thereof, such as the heel only or the ball and shank of the sole only.

20 The character of the invention may be best understood by reference to the following description of one illustrative embodiment thereof shown in the accompanying drawing, wherein—

Figure 1 is a plan of an illustrative sole including a heel made of the composition embodying the invention; and Fig. 2 is a 25 sectional view of the sole taken on the line 2—2 of Fig. 1.

Referring to the drawing, the illustrative sole shown therein as embodying one form 30 of the invention comprises alternate layers of rubber or other suitable flexible and preferably waterproofing material and a different material, preferably a fabric or mass formed of felt intimately impregnated or 35 treated with rubber in any suitable manner. While I have obtained the best results with felt, I may employ certain other fibrous materials, and while I prefer to use rubber as an impregnating material, I may employ 40 any other suitable waterproofing, readily flexible material. I have, however, obtained the best results by the use of rubber. The sole or other article may consist of a single 45 layer of rubber-impregnated felt or other materials, but herein I have represented the sole as composed of a plurality of layers, certain of which may consist wholly of rubber. These layers may vary in number and 50 arrangement as desired.

55 If desired, and within the scope of my

invention, the sole or any suitable part thereof may be composed entirely of rubber-impregnated felt, and in such case, instead of being composed of a plurality of layers, the sole may be composed of a single sheet, strip or layers of rubber-impregnated felt of any suitable thickness. If desired, the sole may be composed of a plurality of layers, any one or more or all of which may be composed of rubber-impregnated felt. 60 Such layer or layers may be co-extensive with the entire sole, or with any desired portion thereof, such as the shank portion of the sole or the heel.

65 As shown herein, the sole comprises two 70 layers of rubber-impregnated felt *a*, *a* appropriately secured together, preferably by vulcanizing. These layers extend along the ball and shank of the sole to and beneath the heel. Layers of rubber or other suitable 75 flexible and preferably waterproofing material, and rubber-impregnated felt, preferably alternating, are vulcanized together and to the portions of the layers extending along the ball of the sole. As shown herein, 80 a rubber layer *b* is secured to the lower fabric layer *a*, a rubber-impregnated layer *c* is secured to the rubber layer *b* and an outer rubber layer *d* is secured to the layer *c*. When these layers are vulcanized together they form in effect a composite integral whole.

85 The heel comprises a layer *e* of rubber secured to the lower felt layer *a*, layers of rubber-impregnated felt *f* secured to the 90 layer *e* and an outer layer *g* secured to the layers *f*. This layer *g* is made thicker than the others to provide the desired cushioning effect. All of these layers are vulcanized together and to the layer *a* to form in effect 95 a heel integral with the shank of the sole.

100 In making rubber heels it is customary to insert therein metal washers for receiving the nails which are driven into the heel in order to distribute the holding effect of the nails to the rubber and thereby tend to prevent the nails from pulling through the rubber. A heel constructed in accordance with my invention eliminates the necessity of the use of these washers since the rubber-impregnated felt is strong and tough and effectively prevents the nails from pulling through. A sole constructed as described 105 has all the advantages of a rubber sole and eliminates many disadvantages thereof.

One great objection to the rubber sole is its weight. Many people deny themselves the advantages of the rubber sole for this reason. The sole described herein is much 5 lighter than the rubber sole, and is more durable. The strong fibers of the felt strip or layer enable the sole to hold the stitching securely, with no liability of its pulling through as in the case of the solid rubber 10 sole. The sole described is waterproof, does not squeak, has great flexibility, and forms a yielding cushion preventing jarring. The felt layer impregnated with rubber is strong and tough. Since some at least of the layers 15 in the sole are, in the disclosed embodiment of the invention, of this strong and tough material, it is not necessary to use so much rubber as in the case of a solid rubber sole and consequently the outer rubber layer, if 20 employed, may be made of a purer, better quality of rubber than formerly without increasing the cost of the sole as a whole. When the outer rubber layer is worn through exposing the felt layer the latter 25 will present an effective wear-resisting surface. While the composition of matter has been described herein as applied to heels and soles for shoes, it will be understood that it may be applied to other uses as desired. 30 Having thus described one illustrative embodiment of my invention, I desire it to be understood that although specific terms are employed, they are used in a generic and descriptive sense and not for purposes 35 of limitation, the scope of the invention being set forth in the following claims.

Claims.

1. A boot or shoe sole, or part thereof, comprising rubber-impregnated felt.
2. A sole having a layer composed of rubber-impregnated felt.
3. A sole comprising alternate layers of rubber and rubber-impregnated felt vulcanized together.
4. A sole comprising layers of rubber-impregnated fabric secured together and extending along the shank and ball of the sole, and alternate layers of rubber-impregnated fabric and rubber vulcanized together and extending along the ball of the sole.
5. A sole composed of a plurality of layers secured together, one of said layers being composed of rubber and another of felt impregnated with rubber.
6. A sole composed of a plurality of layers vulcanized together, one of said layers being composed of rubber and another of felt impregnated with rubber.
7. A boot or shoe sole comprising a layer of rubber-impregnated felt and a layer of waterproof material secured together.
8. A boot or shoe sole comprising a layer of rubber-impregnated felt and a layer of flexible material secured together.

In testimony whereof, I have signed my name to this specification, in the presence of two subscribing witnesses.

RUSSELL T. ELWELL.
